UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

PORTABLE LAMP.

1,275,873.

Specification of Letters Patent. Patented Aug. 13, 1918.

Application filed July 25, 1917. Serial No. 182,747.

To all whom it may concern:

Be it known that I, ETHAN I. DODDS, a citizen of the United States, and a resident of Pittsburgh, in the county of Allegheny and State of Pennsylvania, have invented certain new and useful Improvements in Portable Lamps; and I do hereby declare the following to be a full, clear, and exact description of the invention, such as will enable others skilled in the art to which it appertains to make and use the same.

This invention relates to improvements in portable lamps and particularly to such as employ a small incandescent electric lamp and carry a battery for supplying the filament of the lamp with current,—the object of my present invention being to so construct the lamp that its globe may be rendered luminous by light rays emanating periodically from the incandescent lamp and retain such luminosity for a considerable time after the incandescent lamp shall have been extinguished, and to provide simple and efficient means which will operate to close the circuit of the incandescent lamp at stated intervals to provide light for activating and reactivating the light absorbing material in the globe.

With this and other objects in view, the invention consists in certain novel features of construction and combinations of parts as hereinafter set forth and pointed out in the claims.

In the accompanying drawings; Figure 1 is a view of a portable lamp embodying my improvements; and Fig. 2 is a diagrammatical view illustrating the same.

1 represents a casing which may contain a suitable battery 2 included in the circuit of an incandescent lamp bulb 3 mounted on the casing 1. The fixture of the lamp may be supported on the casing by means of a suitable bracket 4 and the latter also supports two globes 5 and 6,—one within the other. The globe 6 receives and incloses the lamp bulb 3 so that light from the latter will serve to uniformly activate a phosphorescent coating 7 on the inner face of the outer globe 5,—or if desired, this coating may be placed upon the outer surface of the inner globe 6. The coating 7 may comprise such material as zinc or calcium sulfid and a small amount of radioactive material, such as a salt of radium.

55 By flashing the incandescent lamp, the

coating 7 will be activated and it will retain its luminosity for a considerable period after the lamp 3 shall have been extinguished and afford sufficient light to illuminate the surrounding area for ordinary purposes where a mild light is desired.

In order to cause the incandescent lamp to be lighted automatically at stated intervals to reactivate the light absorbing or phosphorescent coating and thus insure the continuity of the glow of the phosphorescent material in the globe 5,—the devices now to be described may be employed.

The battery 2 and lamp 3 may be connected in series with a switch 8. A time mechanism such as a watch or clock movement 9 is located within the casing 1 and its winding stem may project outwardly through the wall of said casing and provided with a head or key 10 which shall be readily accessible for winding the watch or clock. The dial of the movement is provided with two sets of contacts 11—12 spaced at any desired regular intervals, and contact fingers 13—14 carried and electrically connected by a block 15 connected with the spindle of the minute hand of the watch or clock movement, said contact fingers being adapted to wipe over the contacts 11—12 on the dial. All of the contacts of the set 11 are electrically connected in a circuit 16 with one of the terminals of the switch 8, and all of the contacts 12 are connected in a circuit 17 with the other terminal of the switch 8. With such construction, it will be apparent that when the switch 8 is closed, and the spring fingers 13—14 on the time mechanism wipe over contacts 11—12 of the respective series, the circuit of the incandescent lamp will be closed only during such time that the contact fingers 13—14 are passing over the contacts 11—12, and the incandescent lamp will remain lighted for a brief period, but to activate or reactivate the phosphorescent coating. The phosphorescent coating may thus be activated periodically when the switch 8 is closed and the time mechanism is running.

Having fully described my invention what I claim as new and desire to secure by Letters-Patents is:—

1. A lamp comprising a globe and a source of electric light within said globe, phosphorescent material within said globe, and a time operated circuit closer in the circuit of

said source of electric light for periodically closing and opening said circuit.

2. A lamp comprising a globe, a coating of phosphorescent material within the globe, an electric light device within the globe for activating said coating, a time operated circuit closer comprising a movable member and a plurality of stationary contacts included in the circuit of the electric light device.

3. A lamp comprising a casing, a globe mounted thereon, phosphorescent material in said globe, an electric light device within said globe for activating said material, a battery in said casing, an electric circuit in-

cluding said battery and electric light device, a manually operable switch in said circuit, and a time operated circuit closer comprising a movable member and a plurality of stationary contacts coöperable therewith, mounted in said casing and included in said circuit.

In testimony whereof I have signed this specification in the presence of two subscribing witnesses.

ETHAN I. DODDS.
